UNITED STATES PATENT OFFICE.

GWILYM H. TREHARNE, OF CANTON, OHIO.

RAILWAY-TIE.

1,036,749.

Specification of Letters Patent.

Patented Aug. 27, 1912.

Application filed June 22, 1912. Serial No. 705,213.

To all whom it may concern:

Be it known that I, GWILYM H. TREHARNE, a citizen of the United States, residing at Canton, in the county of Stark and State of 5 Ohio, have invented a new and useful Railway-Tie, of which the following is a specification.

My invention relates to improvements in railway ties and has specific reference to the 10 devices employed in securely holding the railway rails upon the ties.

The objects of my invention, are, first, to provide a railway tie constructed of any suitable material for the purpose designed, 15 and second, to provide means for securely locking and holding the railway rails in proper relative positions with reference to the tie.

I attain these objects by the mechanism 20 illustrated in the accompanying drawings, although the inventive idea involved is capable of receiving a variety of mechanical expressions, one of which I have chosen to illustrate the invention.

25 In the accompanying drawings forming part of the specification: Figure 1 is a perspective view showing one set of the rail locking devices removed. Fig. 2 is a longitudinal section of the tie showing one of 30 the railway rails locked and the locking device of the opposite rail removed, said figure being on line 2—2, Fig. 3, except the locking devices are not shown in section. Fig. 3 is a top view of the tie showing the different 35 parts in practically the same relative position as illustrated in Fig. 2, the tread of one of the rails being broken. Fig. 4 is a section on line 4—4, Fig. 2. Fig. 5 is a longitudinal section showing a portion of a tie 40 and a portion of a railway rail, also showing the rail holding dog in position to clamp or lock the base flange of a railway rail, also showing the filling plug in proper position. Fig. 6, is a transverse section on line 6—6, 45 Fig. 5.

Similar numerals of reference indicate corresponding parts in all the figures of the drawings.

In the accompanying drawing, 1 represents 50 the railway tie which may be formed of any suitable material for railway purposes. The railway tie 1 is provided with recesses or chambers 2, the outer ends of said recesses being provided with the enlarged 55 portions 3, which enlarged portions

are for the purposes hereinafter described. Between the recesses or chambers 2 are located the integral rail supports 4, which supports are formed of a width to correspond substantially with the width of the 60 bottoms or bases of the railway rails 5. Within the chambers or recesses 2 are normally located the rail locking or clamping dogs 6, which clamping dogs are provided with the lateral lugs 7, which lugs are for 65 the purpose of preventing any bodily upward movement of the locking dogs. The lugs 7 are seated or located in the grooves 8, which are formed in the side walls of the chambers or recesses 2 as best illustrated in 70 Fig. 4.

It will be understood that in order to provide room for entering the dogs 6 in the recesses 2, said recesses must necessarily be provided with the enlarged portions 3, 75 which permit the entrance of the lugs 7, the locking dogs 6 are provided with suitable apertures 9, through which apertures are located the dog-locking levers 10. When it is desired to secure the railway rails in 80 proper position upon the ties the locking levers 10 are lifted or brought into the position illustrated in the dotted lines Fig. 5 and when in that position the dogs are moved bodily toward the railway rails until 85 the clamping ends of the dogs 6 are brought over and upon the upper faces of the base flanges of the railway rails, after which, the locking levers 10 are brought into the position shown in full lines Fig. 5, and when 90 said levers are brought into the position shown in full lines, the locking levers will lift the ends of the locking dogs upward and away from the bottoms of the recesses 2, thereby forcing the overlapped or opposite 95 ends of the dogs down and upon the upper faces of the flanges of the railway rails.

The dog 6 rocks upon the downward extended portions 11 resting upon the bottoms 100 of the recesses 2. For the purpose of lifting the ends of the dogs 6 to which the locking levers 10 are connected, said locking levers are provided with the shoulders 12, which shoulders come against the bottoms of the 105 locking dogs or more specifically said shoulders are seated in the shallow grooves 13. For the purpose of preventing any accidental displacement of the locking dogs 6 after they have been brought into position 110

to securely hold the railway rails the blocks 14 are provided which blocks are placed in the enlarged portions 3 of the recesses or chambers 2. It will be understood that the 5 blocks 14 should be placed in proper position with reference to the railway ties prior to the time the locking levers 10 are brought into position to bind and hold the railway rails. This is necessary owing to the fact 10 that after the locking levers 10 have been brought into the position shown in full lines Fig. 5 their upper ends or portions will interfere with the placing of the blocks 14.

For the purpose of providing means for 15 removing the blocks 14, said blocks are provided with the lifting knobs 15, which knobs may be of any desired construction, but should be so formed that they will not interfere with the movements of the locking 20 levers 10.

Having fully described my invention what I claim as new and desire to secure by Letters Patent, is—

1. In combination, a tie provided with 25 recesses spaced from each other, the side walls of the recesses provided with grooves, rail clamping dogs provided with lateral lugs, said lateral lugs adapted to be seated in the grooves of the recesses, locking levers pivotally connected to the rail clamping dogs, said locking levers provided with shoulders adapted for contact with the rail locking dog.

2. In combination, a tie provided with 35 recesses, rail supports located intermediate the recesses, said recesses provided with enlarged portions at their outer ends, rail clamping dogs provided with downward extended portions adapted for contact with the bottoms of the recesses, locking levers pivotally

connected to said rail clamping dogs, said locking levers adapted to rock the clamping dogs.

3. In combination, a tie provided with recesses, rail supports located intermediate the 45 recesses, said recesses provided with enlarged portions at their outer ends, rail clamping dogs provided with downward extended portions, adapted for contact with the bottom of the recesses, locking levers 50 pivotally connected to said rail clamping dogs, said locking levers adapted to rock the clamping dogs, and the locking dogs provided with lateral lugs and grooves formed in the side walls of the recesses adapted to 55 receive said lateral lugs.

4. In combination, a tie provided with spaced recesses, rail supports located between the spaced recesses, the side walls of 60 said recesses provided with grooves, rail clamping dogs located in the recesses, said rail clamping dogs provided with pivoted locking levers and blocks located in the outer portions of the recesses.

5. In combination, a tie provided with 65 spaced recesses, rail supports located between the spaced recesses, the side walls of said recesses provided with grooves, rail clamping dogs located in the recesses, said rail clamping dogs provided with pivoted 70 locking levers and blocks located in the outer portions of the recesses, said blocks provided with knobs.

In testimony that I claim the above, I have hereunto subscribed my name in the 75 presence of two witnesses.

GWILYM H. TREHARNE.
